UNITED STATES PATENT OFFICE.

WILLIAM W. ANDERSON, OF CHICAGO, ILLINOIS.

KNOCKDOWN CONVERTIBLE IRONING-BOARD AND TABLE.

1,369,372.

Specification of Letters Patent. Patented Feb. 22, 1921.

Application filed March 15, 1920. Serial No. 365,975.

To all whom it may concern:

Be it known that I, WILLIAM W. ANDERSON, a citizen of the United States, and a resident of Chicago, in the county of Cook and State of Illinois, have invented certain new and useful Improvements in Knockdown Convertible Ironing-Boards and Tables, of which the following, when taken in connection with the drawings accompanying and forming a part hereof, is a specification.

This invention relates to ironing boards and to what are known as kitchen tables.

Among the objects of this invention are to obtain a construction which is convertible from an ironing board having a solid foundation to a table, and back to an ironing board, at the will of the operator; and which when in use as an ironing board will be sufficiently rigid not to slip or move about on the legs and frame thereof; and when used as a table cannot slip or move about on said frame and legs.

Additional objects are to obtain a knock-down convertible ironing board and table which is composed of few parts, which are not liable to be broken or to get out of order; and which when the several parts are in position for the use of the device as a table will present a top having a smooth surface, having no recesses therein, and no bolts, screw heads, or other projections thereon. An additional object is to obtain a device of the character recited in which, when used as a table, the ironing board will be fitted within the frame of the device, out of sight and protected from dust and dirt.

In the drawings referred to Figure 1 is an isometric view of the device, with the several parts in position for its use as a table:

Fig. 2 is the same view, as Fig. 1, with the several parts in position for use as an ironing board:

Fig. 3 is a top plan view of the frame and legs of the device:

Fig. 4 is a vertical section, on lines 4-4 of Fig. 3, viewed in the direction indicated by arrows:

Fig. 5 is a plan view of the top of the device, showing the ironing board above the table top, as in Fig. 2, and

Fig. 6 is a side elevation of the ironing board and table top in the position illustrated in Figs. 2 and 5.

55 A reference character applied to designate

a given part indicates said part throughout the several figures of the drawings, wherever the same appears.

A represents a table top, *a* the smooth surface or side which forms the upper side 60 thereof when the device is in condition for use as a table; and *a'* the face on which an ironing board is mounted, in the manner hereinafter described. B, B represent the end rails and B', B' the side rails of the 65 frame of the device. C, C represent the legs of the device. D represents an ironing board. E, E' represent cleats which are, respectively secured to top A, on face *a'* thereof, as by nails or screws *e*, *e*. F represents a cleat which is secured on said face *a'* of top A, as by nails or screws *f*, *f*. The ends *e'* of cleat E, and the ends *f'* of cleat F, are respectively cut at an angle to the sides thereof, the faces of said ends being 70 in planes which are diagonal to the planes in which the sides extend. The purpose of said diagonal faces is to cause said ends to come close to contact with the inner faces of braces or cleats G, G, when the 75 table top is in the position illustrated in Fig. 1 of the drawings, with the ironing board D thereunder.

By the foregoing described arrangement, when the device is converted into a kitchen 80 table the top A cannot be moved longitudinally or laterally on the frame formed by the rails B, B, B', B'; but may be lifted vertically to be removed therefrom; and face *a* of said top A, may be continuous and 85 smooth, with no cracks, recesses or abutments thereon; for sanitary reasons.

To render the device of a knock-down character the braces G, G, fit, at their ends, into dove-tailed grooves on the inner faces 90 of rails B, B, B', B', respectively, as is well illustrated in Fig. 3 of the drawings; and bolts or lag screws H, H, are extended through said braces and into said legs. To 95 remove the legs from the frame it is simply necessary to remove said bolts or leg screws from said legs.

I, I, represent cushions, preferably made of rubber, which are embedded in the upper edges of the frame, as say in legs C, C, to 100 extend a slight distance above the ends of said legs, so that top A rests thereon, when side *a'* of said top is uppermost. These cushions are particularly designed, with side *a* of the top resting thereon, when the top 105

is in the position illustrated in Fig. 2 of the drawings, (the ironing board being in position for use), to prevent movement of said table top on the frame when the ironing board is used; said face *a* not sliding freely on said cushions.

To assemble the device, the braces G, G, are driven into the dove-tailed grooves in rails B, B', and preferably glued. The 10 frame of the device is thus completed, being substantially similar to ordinary frames of knock-down tables. The cleats E, E' are secured to the under side of the ironing board D, and said cleats, together with cleat F, 15 are secured to side *a'* of top A, as by screws or nails *e*, *e* and *f*, *f*.

In addition to the functions of said cleats as hereinbefore recited, they assist materially in the prevention of warping of said table 20 top.

Legs C, C, being secured to the frame as recited, top A is laid on said frame to rest on cushions I, I, slightly above the upper edges of the side rails B, B'.

25 Said top being laid on said frame with side or face *a* uppermost, (for use of the device as a kitchen table), the ends of cleats E and F are close to contact with the inner faces of braces G, G, and movement of the 30 top, either longitudinally or laterally, on said frame is prevented; while at the same time said top may be lifted vertically and removed therefrom, reversed, and replaced thereon, with side *a'* resting on cushions I, I; 35 the ironing board D being in position for use. When in this position said side *a'* adheres to said cushion in a manner to lessen, in a great measure, the tendency of the top to move or slide about on the frame.

40 When it is desired to have the top A, it being placed on the frame formed by the end and side rails in the manner illustrated in Fig. 1, rest directly on the upper edges of said rails, the recesses J, J, are made in side 45 *a'* of said top, to admit cushions I, I, thereto. (See Fig. 5.)

I claim:

1. In a convertible ironing board and table, a frame comprising side rails, end rails and means comprising braces to join 50 said side and end rails, in combination with a top removably mounted on said frame, an ironing board secured on one side of said top in spaced relation thereto, and cleats also secured on said last side, the ends of 55 said cleats arranged to abut against said braces when said top is on said frame with said cleats and ironing board on the under side thereof.

2. A frame, in a convertible ironing board 60 and table, comprising side rails, end rails, and means comprising braces to join said side and end rails, and cushions extending above the upper edges thereof, in combination with a top removably mounted on said frame, an ironing board, a plurality of means to secure said board on one side of said top in spaced relation thereto, and a cleat also secured on said last side, the ends 65 of one member of said plurality of means and of said cleat arranged to abut against said braces when said top is placed on said frame to rest on said cushions with said ironing board and cleat on the under side of 70 said top.

3. In a convertible ironing board and table, a frame comprising side rails, end rails and means to join said side and end rails, and cushions extending above the upper edges thereof, in combination with a 80 top removably mounted on said frame to rest on said cushions, and an ironing board secured on one side of said top in spaced relation thereto, said ironing board arranged to be inclosed by said frame when said top 85 rests on said cushions with said ironing board on the under side thereof.

WILLIAM W. ANDERSON.

In presence of—

CHARLES TURNER BROWN,
B. S. BROWN.
